COMBINATION BRASSIERE-GIRDLE

Ethel R. Kaupp, New York, N. Y.

Application September 27, 1954, Serial No. 32,440

Term of patent 7 years

(Cl. D20—2)

Fig. 2.

Fig. 1.

Fig. 1 is a front elevational view of a combination brassiere-girdle showing my new design; and,

Fig. 2 is a rear elevational view thereof.

I claim:

The ornamental design for a combination brassiere-girdle, substantially as shown.
